TOY BANK

Marvin I. Glass and John W. Ehemann, Chicago,
Ill., assignors to Marvin I. Glass, Chicago, Ill.

Application May 17, 1951, Serial No. 226,886

1 Claim. (Cl. 46—3)

1

This invention relates to toy banks, and more particularly to a toy bank which is actuated by the insertion of a coin.

One of the objects of this invention is to provide a toy bank in the form of an animal with a movable body member, such as a tail, which is normally stationary but which is actuated to wag when a coin is deposited and to continue wagging for a short period of time.

Another object is to provide a very simple and inexpensive toy bank which by reason of the action produced will encourage a child to deposit coins therein.

Other objects will become apparent as this description progresses.

In the drawings:

Fig. 1 is a side view of the toy bank with a portion broken away and partially in cross section to show the interior thereof.

Fig. 2 is a view taken on the line 2—2 of Fig. 1.

Fig. 3 is a perspective view and showing in dotted lines the operating parts.

The figure shown in the drawings is that of a dog, but it will be understood that any animal character may be used. The housing, generally indicated at 10, is shaped to simulate a dog and is formed of two longitudinal body sections 12 and 14 permanently joined together.

The head 16 of the dog has a mouth portion which is in the form of a transverse slot 18. The opposite walls 20 and 22 of the slot extend downwardly at an inclined angle and into the interior of the housing.

A longitudinally extending inclined wall partition 24 extends from the wall 22 to the rear of the housing and the same has a depending well portion 26. The inclined wall partition divides the interior of the housing into an upper and lower compartment. The upper compartment 28 contains the operating parts while the lower compartment 30 forms the container for the coins.

Suitably anchored within the well 26 is a leaf spring 32 which extends upwardly through a transverse slotted opening 34 adjacent the upper rear end of the housing. Secured to the opposite end of the spring is a tail member 36 whose lower portion 37 covers the length and width of the slotted opening 34 so that when the tail is wagging, as will be subsequently described, the slotted opening will be covered.

Pivottally supported as at 38 on the inclined partition wall 24 is an actuating member or arm, generally indicated at 40, which has a bifurcated rear end 42 between which the spring 32 ex-

2

tends. The front end of the actuating member 40 extends upwardly as at 44 and terminates in a flat forwardly and downwardly extending portion 46 which passes through aligned slots 47 and 48 respectively, in the walls 20 and 22 and intercepts the coin slot 18 to block the deposit of a coin. The normal position of the operating parts is as shown in full lines in Fig. 2, with the bifurcated end 42 of the actuating member 40 out of engagement with the spring 32 and the tail 36 in a stationary vertical position. When a coin 50 is deposited in the slot 18, it will engage the edge 52 of the forwardly extending portion 46 of the actuating member 40 and rock the same 15 clockwise to the dotted line position of Fig. 2, causing the bifurcated end 42 to engage the spring 32 and displace it from its vertical position, moving with it the tail 36 supported thereon. After the coin has cleared the forwardly extending portion 46, it drops into the hollow body compartment 30 and is retained therein until removed. Simultaneously the spring 32 which has been placed under a bending stress will move the operating member 40 back to the full line position of Fig. 2, and the spring 32 and tail 36 will continue to wag or oscillate back and forth for a period of time until it comes to rest. Thus, with every deposit of a coin, the tail is caused to wag for an interval of time, indicating to the child that the dog is happy to receive the coins, thus encouraging a child to save.

The coins deposited in the bank compartment 30 will not engage any of the operating parts and the coins may be removed from the bottom thereof by any conventional means, such as providing an opening in the bottom of the compartment which is closed by a removable plate which may be locked by a key or by manual manipulation.

The housing, as well as the operating parts, except the spring, may be made of plastic or like material. It will be understood that various changes and modifications may be made from the foregoing without departing from the spirit and scope of the appended claim.

45 We claim:

In a toy bank comprising a body shaped to simulate an animal, a partition interiorly of said body dividing the same into an upper and lower compartment, said body having a coin slot 50 through said body aligned with a coin opening in the partition to receive coins into the interior of said lower compartment, said upper compartment having an opening adjacent the rear thereof, an elongated spring member secured at one end within said body and extending through said

opening and comprising a tail simulating portion exteriorly of said body, an actuating member pivotally mounted on said partition within said upper compartment and extending longitudinally between said spring and said coin slot, with the rear end thereof contacting the side of the spring member and the front end engageable by a coin inserted into coin slot for pivotally moving the actuating member to laterally stress the spring to cause said tail to wag when the coin passes the actuating member and falls into the lower compartment.
